UNITED STATES PATENT OFFICE.

ALFRED F. DONOVAN, OF BOSTON, MASSACHUSETTS, ASSIGNOR TO E. T. WRIGHT & CO., INC., OF ROCKLAND, MASSACHUSETTS.

DESIGN FOR A SHOE.

Application filed September 24, 1927. Serial No. 23,541. Term of patent 3½ years.

To all whom it may concern:

Be it known that I, ALFRED F. DONOVAN, a citizen of the United States, residing at Boston, in the county of Suffolk and State of Massachusetts, have invented a new, original, and ornamental Design for Shoes, of which the following is a specification, reference being had to the accompanying drawing, forming part thereof, and in which—

I claim:

The ornamental design for a shoe as shown.

ALFRED F. DONOVAN.
